UNITED STATES PATENT OFFICE.

HERMAN H. DIEHL, OF HUNTINGTON, WEST VIRGINIA, ASSIGNOR TO THE WEST VIRGINIA RAIL COMPANY, OF HUNTINGTON, WEST VIRGINIA, A CORPORATION OF WEST VIRGINIA.

TRACK CONSTRUCTION.

Application filed March 22, 1923. Serial No. 626,889.

To all whom it may concern:

Be it known that I, HERMAN H. DIEHL, a citizen of the United States, residing at Huntington, in the county of Cabell and State of West Virginia, have invented a new and useful Improvement in Track Constructions, of which the following is a specification.

My invention relates more particularly to the securing of rails to ties especially in the case of track-construction for use in mines and general construction work.

Certain of my objects are to provide a novel, simple and economical arrangement of parts; to provide a construction which will permit of the rails being readily and quickly secured in place on the ties and removed therefrom when desired; to provide on the clip a rail-gauging portion so formed as to insure, under all conditions, the proper gauging of the rail; and to provide a construction which will permit of the assembly with rails securely held in place on ties, of extension rails laid on their sides parallel with relation to the fixed rails, in accordance with the practice known as "balling" the rails.

Referring to the accompanying drawing:

Figure 1 is a plan view of a portion of a track-construction embodying my improvements, the tie forming a part thereof being broken away between its ends. Figure 2 is an enlarged section taken at the line 2 on Fig. 1 and viewed in the direction of the arrow, an extension rail, shown by dotted lines, being shown as applied to the rail secured to the tie, in accordance with the "balling" practice above referred to. Figure 3 is an end view of the structure shown in Fig. 1, the structure being viewed from the right-hand side of Fig. 1. Figure 4 is a bottom plan view of one of the similar pivoted rail-flange-engaging clip-plates; and Figure 5, a view in front elevation of the clip of Fig. 4.

In the particular, illustrated, embodiment of my invention the tie is represented at 5 and the parallel rails superposed thereon, at 6. The tie shown is of metal shaped to present the parallel ribs 7 extending lengthwise of the tie, the side-walls of the ribs 7, and represented at 8, being preferably relatively abrupt, as shown. The tie is provided adjacent the inner flanges 9 of the

rails, with stationary abutments 10 which may be secured to the tie in any desirable way, as, for example, by the rivets 10^a, the edges of the abutments 10 adjacent the rails being undercut, as represented at 11, to provide portions 12 which overlap the inner flanges 9 of the rails. The tie adjacent the outer flanges 13 of the rails is provided with pivoted clips 14, shown as of plate-form, for engaging the flanges 13 and cooperating with the abutments 10 for holding the rails in place on the tie. The clips 14 are all of the same construction each being pivoted between its ends to the tie, the pivoting means being preferably an ordinary rivet, represented at 15, which extends through an opening 16 in the clip 14, preferably midway between its lateral edges and an opening 17 in one of the ribs 7 preferably midway between the lateral edges of the latter. The end of the clip 14 adjacent the rail is so shaped as to adapt it, when in rail-securing position, to overlap the flange of the rail with which it engages as shown in Figs. 1 and 2, this being preferably accomplished by forming this end of the clip with an upwardly-deflected portion represented at 18, and as a desirable means for gauging the rails and holding them from spreading, a depending lug 19 is formed on the portion 18 of the clip which engages the outer edge of the flange 13 as shown, the lug 19, which extends only part way across the clip, terminating at one side thereof in a depending flange 19^a. The end of the clip opposite that which overlaps the rail-flange is provided on its under side, at its longitudinal edges, with a pair of depending parallel ribs 20 spaced apart a distance substantially equal to the width of the upper surface of the tie-rib 7 as shown in Fig. 3, the provision of the ribs 20 causing the clip 14 to present a channel 21 along its under-side. The outer end of the clip 14 is provided with an upwardly-extending lug 22 shown as integral with the body of the clip and preferably formed by upwardly deflecting this end of the clip.

The clip, which is preferably rolled to shape, is formed preferably of steel, whereby it is caused to be springy, and the rivet 15 extends loosely through the clip, the parts being preferably so proportioned that the clip may freely rotate on the tie when

the rail is not in place thereon, but when a rail is positioned against the adjacent abutment 10 it will require the application of considerable force to the clip in a direction for rotating the clip, and the flexing of the clip against its inherent springiness, to rotate the clip from a position crosswise of the tie into a position in which it extends parallel with the ribs 7 and engages the rail, the flexing referred to occurring in the riding of the ribs 20 against the rib 7 of the tie with which it cooperates, and the riding of the portion 18 against the inclined top surface of the rail-flange 13, it being understood that when the clip reaches a position in which it extends parallel with the rib 7 its outer end springs downwardly to receive the rib 7 within the channel 21 of the clip, thereby locking the clip against accidental rotation out of rail-flange-engaging position. Furthermore the parts are so proportioned that the clip when in rail-flange-engaging position, as shown, will, under its spring action, bear down at its opposite ends against the rail flange and the tie, respectively. In the positioning of the clip 14 as stated the lug 19^a extends into the groove presented between the two tie-ribs 7 and extends adjacent a side of the one of the ribs 7 to which it is pivoted, for the purpose hereinafter described.

The clips, in practice, would ordinarily be driven into rail-flange-engaging position, by striking the clips with a hammer, the upwardly-extending lug 22 affording a part to be struck, and permitting the workmen to more readily direct the hammer blows against the clip, for the purpose stated.

It is desirable, especially in track-construction for mines, that the tie and rail-securing means be provided as a unit, in assembled relation, as distinguished from providing the tie and securing means as separated parts requiring assembly in securing a rail to the tie, it being understood from the foregoing that my improved construction permits of the following of the above-referred-to desired practice, as the clips and abutments may be furnished in assembled position on the tie and when a track is to be laid, all that is required is the application of the rails to the ties and the rotating of the pivoted clips to rail-flange-engaging position. It will furthermore be noted that in the disassembling of the rails and ties all that is required to release the rails from the ties is to drive the clips out of rail-engaging position.

It will be noted that, in the particular construction shown, the inner edge of the abutment is relatively widely spaced from the vertical flange of the rail, as shown in Fig. 2, this permitting of the "balling of the rail", as it permits the head of the rail, when the latter is laid on its side as shown

by dotted lines in this figure, to be received between the abutment 12 and the rail-web, the flange of the rail resting on the tie. Rails positioned at opposite sides of the fixed rails, as shown, in dotted lines, of one rail in Fig. 2, may be readily slid along the fixed rails to the desired degree of protrusion beyond the latter in which position their webs afford a track upon which the wheel-flanges run after the wheels pass beyond the ends of the fixed rails. In this connection it may be stated that the abutment 12 serves to hold the "balled" rail in place, this abutment being preferably of the form shown as thereby it serves in a highly effective manner not only as an abutment for the rail secured to the tie but also as an abutment for the balled rail. The depending lug 19^a serves as a rail-gauging means, shown as supplementing the gauging portion 19, and its purpose is to positively prevent, under all conditions, the lateral displacement of the rail on the tie out of the proper gauged position. In this connection it may be stated that, under some conditions, as for example by corrosion of the parts, the rail-flange might enter between the tie and the lip 19, where the lip 19 only is provided, and by exerting a wedging action on the clip move laterally out of gauged position, but by providing the lug 19^a, the action above referred to is prevented and the rail is maintained in proper gauged position at all times.

While I have illustrated and described a particular construction embodying my invention, I do not wish to be understood as intending to limit it thereto as the same may be variously modified and altered without departing from the spirit of my invention. In this connection it will be understood that a plurality of the clips 14 may be used at each end of the tie, instead of one as shown, and that the position of the clips 14 and abutments 10 may be reversed, viz., by locating the abutments 10 at the outer flanges of the rail and the clips 11 at the inner flanges thereof.

What I claim as new, and desire to secure by Letters Patent, is:

1. In track-construction, the combination of a tie presenting upwardly-extending, relatively abrupt, surfaces spaced apart, and a clip, having a rail-flange-engaging portion, pivoted between its ends on said tie and rotatable thereon about its pivot and presenting downwardly-extending, relatively abrupt surfaces spaced apart, the said surfaces on said tie and clip interlockingly engaging when said clip is in rail-flange-engaging position.

2. In track-construction, the combination of a tie presenting upwardly-extending, relatively abrupt, surfaces spaced apart, and a spring clip, having a rail-flange-engaging

- portion, pivoted between its ends on said tie and presenting downwardly-extending, relatively abrupt surfaces spaced apart, the said surfaces on said tie and clip interlockingly engaging when said clip is in rail-flange-engaging position. 5
3. In track-construction, the combination of a tie and a clip pivoted between its ends on said tie and having a rail-flange-engaging portion at one end and an upwardly-extending portion at its opposite end, said tie and clip having portions which interlock against imposed resistance in the rotation of the clip to rail-flange-engaging position. 10
- 15 4. In track-construction, the combination of a tie, and a spring clip pivoted between its ends on said tie and having a rail-flange-engaging portion at one end and an upwardly-extending portion at its opposite end, said tie and clip presenting portions which interlock in the rotation of said clip to rail-flange-engaging position, and the parts being so proportioned that said clip is required to flex in rotating it to rail-flange-engaging position. 20
- 25 5. In track-construction, the combination of a tie presenting upwardly-extending surfaces spaced apart, and a spring clip pivoted between its ends on said tie and having a rail-flange-engaging portion at one end and parallel depending ribs at its opposite end adapted to interlock with said surfaces of said tie when said clip is in rail-flange-engaging position, the underside of said clip between its ends at the pivoted point of said clip being of a thickness substantially equal to the thickness of said clip at the ribs thereon. 30
- 35 6. A rail-clip comprising a body containing a pivoting opening between its ends, the under surface of said body at one end being in a higher plane than the under surface of said body at said opening and having a depending boss, the under surface of said body at its opposite end being formed with depending ribs spaced apart and extending lengthwise of said clip and presenting a channel, said portion of the clip in which said opening is located being of substantially uniform thickness throughout its cross-sectional area and of a thickness substantially equal to the thickness of the clip at its ribs. 40
- 45 7. In track-construction, the combination of a tie, and a spring clip pivoted between its ends on said tie and having a rail-flange-engaging portion at one end, said tie and clip presenting portions at its opposite ends which interlock in the rotation of said clip to rail-flange-engaging position, and the parts being so proportioned that said clip is required to flex in rotating it to rail-flange-engaging position. 50
- 55 8. In track-construction, the combination of a tie presenting upwardly-extending surfaces spaced apart, and a spring clip pivoted
- between its ends on said tie and having a rail-flange-engaging portion at one end and parallel depending ribs at its opposite ends adapted to interlock with said surfaces of said tie when said clip is in rail-flange-engaging position. 70
9. In track-construction, the combination of a tie, and a spring pivoted between its ends on said tie and having a rail-flange-engaging portion at one end provided with a track-gauging portion, said tie and clip presenting portions at opposite sides of said pivot which interlock in the rotation of said clip to rail-flange-engaging position, one of the said interlocking portions of said clip having a depending flange located adjacent a lateral edge of said track-gauging portion. 75
10. In track-construction, the combination of a tie presenting upwardly-extending surfaces spaced apart, and a spring clip pivoted between its ends on said tie and having a rail-flange-engaging portion at one end and parallel depending ribs at its opposite end adapted to interlock with said surfaces of said tie when said clip is in rail-flange-engaging position, said clip being provided adjacent its rail-flange-engaging portion with a depending flange which, when said clip is in rail-flange-engaging position, interlocks with one of said surfaces of said tie. 80
11. A rail-clip provided with a rail-flange-engaging portion having a depending rail-gauging portion, and a depending flange located adjacent a lateral edge of said rail-gauging portion. 85
12. A spring rail-clip having a rail-flange-engaging portion provided with a depending rail-gauging portion and a depending flange adjacent a lateral edge of said rail-gauging portion, said clip being provided at its opposite end with means adapting the clip to interlock with a tie to which it is applied. 90
13. A spring rail-clip having a rail-flange-engaging portion provided with a depending rail-gauging portion and a depending flange adjacent a lateral edge of said rail-gauging portion, said clip being provided at its opposite end with depending ribs extending lengthwise of the clip, for the purpose set forth. 110
14. A spring rail-clip having a rail-flange-engaging portion provided with a depending rail-gauging portion extending part way only across said clip and a depending flange adjacent a lateral edge of said rail-gauging portion, said clip being provided at its opposite ends with depending ribs extending lengthwise of the clip, for the purpose set forth. 115
15. A rail-clip provided with a rail-flange-engaging portion having a rail-gauging portion a part of which extends above the under side of the body of the clip and is adapted to extend directly above the tie. 120
- 125
- 130

when the rail-clip is positioned thereon, and another part of which is located laterally of the first-referred-to part and extends below the under side of the body of the clip.

- 5 16. In track construction, the combination with a tie and a rail thereon, of a clip secured to the tie and having a rail-gauging portion a part of which extends above the plane of the portion of the tie upon which 10 the rail rests and directly above the tie, and another part of which is located laterally

of the first-referred-to part and extends below the plane of the portion of the tie upon which the rail rests.

17. In track construction, the combination 15 with a tie, and a rail thereon, of a clip pivotally mounted on the tie and having a rail-gauging portion which extends both above and below the plane of the portion of the tie upon which the rail rests when the clip 20 is rotated to rail-gauging position.

HERMAN H. DIEHL.
